(57) **CLAIM**

The ornamental design for a pump nozzle adapter, as shown and described.

DESCRIPTION

FIG. 1 is a top perspective view of a pump nozzle adapter.
FIG. 2 is a bottom perspective view of the pump nozzle adapter.

FIG. 3 is a rear view of the pump nozzle adapter.

FIG. 4 is a front view of the pump nozzle adapter.

FIG. 5 is a left-side view of the pump nozzle adapter.

FIG. 6 is a right-side view of the pump nozzle adapter.

FIG. 7 is a top view of the pump nozzle adapter.

FIG. 8 is a bottom view of the pump nozzle adapter.

FIG. 9 is an alternative top perspective view of a pump nozzle adapter.

FIG. 10 is an alternative bottom perspective view of the pump nozzle adapter.

FIG. 11 is an alternative rear view of the pump nozzle adapter.

FIG. 12 is an alternative front view of the pump nozzle adapter.

FIG. 13 is an alternative left-side view of the pump nozzle adapter.

FIG. 14 is an alternative right-side view of the pump nozzle adapter.

FIG. 15 is an alternative top view of the pump nozzle adapter; and,

FIG. 16 is an alternative bottom view of the pump nozzle adapter.

(Continued)

The broken lines, if any, shown in the drawings illustrate environmental structure and form no part of the claimed design.
